UNITED STATES PATENT OFFICE.

SAMUEL P. SHUEY, OF LAKEMP, OKLAHOMA.

FOLDING BOX.

1,222,581.

Specification of Letters Patent. Patented Apr. 10, 1917.

Application filed April 8, 1916. Serial No. 89,812.

To all whom it may concern:

Be it known that I, SAMUEL P. SHUEY, a citizen of the United States, residing at Lakemp, in the county of Beaver and State of Oklahoma, have invented certain new and useful Improvements in Folding Boxes; and I do hereby declare the following to be a full, clear, and exact description of the invention, such as will enable others skilled in the art to which it appertains to make and use the same.

This invention relates to new and useful improvements in folding boxes and the principal object of the invention is to provide a device adapted for the shipment of eggs or any other product which may be folded after having been used and returned to the shipper in such a condition as to occupy a minimum amount of space.

Another object of the invention is to provide a device which may be constructed of any suitable material and which is folded in a novel manner which will enable it to be easily and quickly folded or unfolded.

A still further object of the invention is to provide a novel means for locking the device in its unfolded position.

A further and more specific object of the invention is to provide a locking means for the central partition to hold the same in its open position and also to provide a device which is adapted to coöperate with the lid lock to hold the lid in closed position when the device is in use.

With these and other objects in view, the invention consists in the novel combination and arrangements of parts which will be fully set forth in the following specification and accompanying drawings, in which:

Figure 1 is a perspective view of a crate or box constructed in accordance with this invention.

Fig. 2 is an end view of the device showing it with the end walls folded.

Fig. 3 is a perspective view of the device showing the same with the end walls folded and the front wall partly folded.

Fig. 4 is an end view of Fig. 3.

Fig. 5 is a perspective view of the device as it would appear when in its folded position.

Fig. 6 is a sectional view through the device showing the same in its open position, and

Fig. 7 is a fragmentary horizontal sectional view illustrating in detail the means

for holding the end walls and the central partition wall in their unfolded position.

Referring to the drawings the numeral 1 designates the front wall of the device which is hinged to the bottom 2 as at 3. The opposite ends of the bottom 2 are provided with upturned flanges 4 which are formed in their opposite ends with suitable openings for the reception of the pivot pins by which the front and rear walls are pivotally connected in place. The front wall 1 is provided at opposite ends with the inturned flanges 5, the inner edges of which are inclined as at 6 so that when the device is folded a space will be left for the accommodation of the pivot of the rear wall which will be more fully hereinafter described. The rear wall of the device is designated by the numeral 7 and provided at opposite ends with the inturned flanges 8 which are provided at their lower terminals with openings to aline with the openings in the rear ends of the flanges 4 and are adapted to receive the pivot pins 9 by means of which the rear wall is pivotally connected in place. The flanges 8 are formed by the attaching of suitable angle members to the rear wall and the terminals of the rear wall near its upper edge are bent inwardly as at 10 to form locks for engagement with the end walls when they are in their raised position to hold them upwardly. Like the rear wall 7 the front wall 1 is provided with angle plates which form the flanges 5 and the opposite ends of the front walls at its upper edge are slightly bent inwardly to form latches which conform to the latches formed by the bent portions 10 which coöperate therewith in supporting the end walls in a raised position. The cover is designated by the numeral 11 and is hinged as at 12 to the upper edge of the rear wall as clearly illustrated in the drawings. The central partition wall of the device is designated by the numeral 13 and is hinged as at 14 to the bottom wall and the upper end of its forward edge is adapted to be engaged by the outwardly bent portions 15 of the eye 16 which projects through the front wall 1 and forms a fastening means for the cover when the device is in use.

Upon reference to the drawing it will be seen that in order to collapse the box the end walls designated by the numeral 17 which are hinged to the bottom wall are swung inwardly and the front wall 1 is then swung

downwardly on its pivot and against the outer sides of the end walls thereby completely inclosing the same. When the wall 1 has reached its lower limit of movement it 5 will be seen that the inclined edges 6 will escape the pivot 9 and the rear walls 7 may then be swung downwardly to completely cover the front wall. The cover 11 is then 10 swung so as to lie on top of the rear wall and it will be seen that the device will present the appearance illustrated in Fig. 5 and will occupy a minimum amount of space when being returned to the shipper. In 15 order to open the device ready for use it will be evident that the rear wall is swung upwardly on pivot 9 and the front wall is then swung on its pivot 3 so as to assume the position shown in Fig. 2 whereupon the end walls are swung upwardly and it will be evident 20 that when they reach their upper limit of travel they will be engaged by the ends of the latch members 10 and will be prevented from moving inwardly thereby. The central partition wall 13 is then swung upwardly 25 on its hinge 14 and moves so that its forward edge near the upper end is positioned between the outwardly bent portions 15 of the eye 16 and will thus be held against accidental collapsing. The cover 30 may then be closed and a suitable locking means may be carried by the forward edge which will coöperate with the eye 16 in holding the cover tightly in place.

While in the foregoing there has been 35 shown and described the preferred embodiment of this invention, it is to be understood that such changes may be made in the combination and arrangement of parts as will fall within the spirit and scope of the 40 appended claims.

What is claimed is:—

1. A folding crate comprising a bottom wall having upturned flanges at opposite ends, a front wall having inturned flanges at opposite ends, pivot pins extending through the flanges and pivotally connecting the front and bottom walls, a rear wall having flanges at opposite ends, pivot pins extending through the flanges at the bottom and

50 rear walls to pivotally connect the same, inclined edges on the flanges of the front wall for accommodating the pivot pins of the rear wall when the front wall is lowered, a cover hinged to the free edge of the rear wall, a central partition wall hinged to the bottom 55 wall, end walls hinged to the bottom wall near the flanges, inturned latch members at the upper edges of the front and rear walls adjacent their flanges and adapted to engage and hold the end walls in raised position, an eye extending through the front wall, and right angle projections at the inner end of the eye adapted to engage and hold the partition wall in its raised position. 60

65 2. A folding crate comprising a bottom wall, angle members secured to the opposite ends of the bottom wall, flanges on the angle members extending upwardly from the bottom wall, a front wall, angle members secured to opposite ends of the front wall, flanges on the angle members extending inwardly from the front wall, pivot pins hinged connecting the flanges of the front and bottom walls, the inner edges of said flanges 70 being cut away, a rear wall, angle members on the ends of the rear wall, pivot pins extending through the angle members of the rear wall and the angle members of the bottom wall to hingedly connect the bottom 75 and rear walls, the cut away portion of the angle members of the front wall accommodating the pivot pins to the rear wall when the front wall is folded, end walls hinged to opposite ends of the bottom, a central partition wall hinged to the bottom, inturned 80 corners at opposite ends of the front and rear walls, said corners forming latches to engage the end walls and hold the same in a raised position and a cover for closing 85 the whole. 90

In testimony whereof I affix my signature in presence of two witnesses.

SAMUEL P. SHUEY.
